UNITED STATES PATENT OFFICE.

GEORGE M. WOLFE, OF MALTBY, WASHINGTON.

EDUCATIONAL CARD SYSTEM.

1,280,930.

Specification of Letters Patent.

Patented Oct. 8, 1918.

Application filed March 28, 1917. Serial No. 157,869.

To all whom it may concern:

Be it known that I, GEORGE M. WOLFE, a citizen of the United States, residing at Maltby, in the county of Snohomish and State of Washington, have invented certain new and useful Improvements in Educational Card Systems, of which the following is a specification.

My invention relates to improvements in educational card systems and has for its principal object to provide an improved and novel system and arrangement of groups of cards to facilitate the teaching of such subjects as reading, spelling, arithmetic and grammar by a process of mechanically building words, sentences, numbers, problems, etc. A further object of my device is to provide a system in which the card bearing a certain common portion of a group of words is arranged adjacent to the cards bearing the remaining portions of said groups of words, whereby the relationship of the common portions of groups of words to the remaining portions of such words may be mechanically shown.

Other objects will appear as my invention is more fully explained in the following specification, illustrated in the accompanying drawings and pointed out in the appended claim.

In the drawings, Figure 1 is a plan view of my device shown laid out flat in an open position. Fig. 2 is an end elevation of same in an upright position as held by the operator.

Referring more particularly to the drawings, numeral 1 indicates a handle, upon the top of which a cross bar holder 2 is secured. The cross bar 2 is provided with a series of wire loops 3, upon which are swingably and removably mounted groups of cards 4 and 5. The groups 4 and 5 here illustrated are for word building and are arranged as shown in Fig. 1. It will be noted that group 4 is made up of a series of cards, having indexed cards arranged in a predetermined order with the indexing and instructions for combining with cards of the group 5, written upon the face of the card which is toward the operator. It will be noted that at the top of the card in group 4 which is shown facing the operator, the note indicates to the operator the phonogram which is displayed toward the pupils; in the case

instructions so state. On the lower portion of the card are listed the index references to cards in group 5 which are to be combined rotatively with phonogram "AID" in order to build predetermined words. It will be noted in the case in hand that in the top of the second column on the card displayed in group 4, we find the reference 30—BR, and that upon looking in group 5, it will be noted that the next card displayed is 31, and it will follow that the previous card which has been turned over toward the pupils in order to build a word with "AID" as an ending must be card 30. Upon examining card 30 which has been turned over, it will be found to contain "BR." I have now utilized the cards to build the word "BR—AID, BRAID." After the word has been taught the pupils, the next card in group 5 to be turned over will be card 47 upon which is written ST, which makes the word "ST—AID, STAID." It will be noted that the indexing on the cards in group 5 corresponds to the references listed on the cards of group 4. Only a portion of the complete word group is here shown in order to make the example as simple as possible. It will be seen that the index on the face of any given card in group 4 applies to the suffix which is upon the reverse side of the next previous card and also that the indexing upon the face of any card in group 5 refers to the characters upon the reverse side of said card. Any card in group 4 may be selectively combined with any other card in group 5 in order to build up a predetermined word. It is obvious that other characters may be used upon the cards equally well, such as complete words to build sentences, digits to build numbers, also words which are derived from a common root may be grouped with the said root. Applicant wishes it understood that he has perfected and used other groups of cards as pointed out above having different connections from those shown and that the same have been used in schools, by other teachers.

While I have shown a particular form of embodiment of my invention, I am aware that many minor changes therein will readily suggest themselves to others skilled in the art without departing from the spirit and scope of the invention, and I therefore desire to avoid being limited to the exact form shown and described.

Having described my invention, what I claim as new and desire to protect by Letters Patent, is—

In an educational card system, the combination of a plurality of correlated groups of cards the groups independently and swingably mounted adjacent to one another upon a holder; marginal monogram indexes upon the obverse side of each card 10 of each group; characters upon the reverse side of each card of each group, the char-

acters on the cards in one group being arranged to form pre-determined words with selected cards of the other groups, instructions upon the face of the cards of one of 15 the said groups, said instructions referring to the characters upon the reverse side of the next previous card in the same group and to the characters upon the opposite sides of certain other cards in the other groups. 20

In testimony whereof I affix my signature.

GEORGE M. WOLFE.
